UNITED STATES PATENT OFFICE.

JAMES LEATHEM, OF LEBANON, PENNSYLVANIA.

SEWING MACHINE.

Application filed September 15, 1920. Serial No. 410,472.

To all whom it may concern:

Be it known that I, JAMES LEATHEM, a citizen of the United States, and a resident of Lebanon, in the county of Lebanon and State of Pennsylvania, have invented certain new and useful Improvements in Sewing Machines, of which the following is a specification.

This invention relates to sewing machines, employing a needle having reciprocating as well as oscillating movements such as are used in the stitching of hemstitched seams and the objects of the invention are to simplify and improve the construction of such machines and increase their efficiency of operation so that the same can be run at very high speeds.

The accompanying drawings illustrate one embodiment of my invention, in the several figures of which like parts are similarly designated.

In the drawings:

Figure 1 is a front elevation of a sewing machine made in accordance with the present invention, shown partly in section and parts broken away for clearness of illustration.

Figure 2 is a bottom view of the sewing machine shown in Figure 1.

Figure 3 is an end view, partly in section and with parts broken away, of the sewing machine shown in Figure 1.

Figure 4 is a sectional view, with parts broken away on the line 4—4 of Figure 3.

Figure 5 is a sectional view, with parts broken away on the line 5—5 of Figure 1.

Figure 6 is a sectional view, with parts broken away on the line 6—6 of Figure 1.

Figure 7 is an enlarged sectional view, with parts broken away of the rear side of the head of the machine.

Referring to the drawings, 1 designates a bed plate; 2 an overhanging hollow arm in which is mounted a needle bar actuating shaft 3 by means of bearing blocks 4. The forward end of the actuating shaft 3 has rigidly secured thereto one end of a crank arm 5 to the other end of which is rotatably mounted one end of a short link 6 the other end of which is rotatably mounted an adjustable stud bearing 7 secured to a needle bar 8 suitably mounted in the overhanging arm, the needle bar being reciprocated by the oscillations of the actuating shaft to which it is connected as follows:—

The rearward end of the actuating shaft 3

has adjustably secured thereto one end of a crank arm 9 to the other end of which is rotatably mounted one end of a connecting rod 10 the other end of which is rotatably mounted on a crank 11 forming part of a main driving shaft 12 mounted in suitable bearing blocks 13, 14 and 15 secured to the bottom of the bed plate.

The rotation of the main driving shaft 12 through the medium of a suitable pulley 16 acts to reciprocate the connecting rod 10 which oscillates the actuating shaft 3 and it in turn acts through the crank arm 5 link 6 and stud bearing 7 to reciprocate the needle bar 8.

The lower end of the needle bar 8 is provided with a slotted bearing block 17 in which is pivotally mounted by means of a tapered pin 18 the lower end of a needle actuating lever 19 having at its lower end and preferably integral therewith, a needle holder 20 for holding a needle 21. The needle bearing block 17 is also provided with means for holding a piercer 22. The upper end of the needle actuating lever 19 is pivoted to a cross head 23 which is arranged to slide in a suitable groove or raceway 24 in a needle oscillating lever 25, in the present instance made L shape. The upper end of the needle oscillating lever 25 is arranged to fit in a groove 26 in the forward end of the arm in which it is pivoted by means of a pin 27, the lower end of the lever 25 is also arranged to fit in a groove 28 in the forward end of the arm, the same being pivotally connected, by means of a pivot pin 29, to the forward end of a link 30. The rearward end of the link 30 is pivotally connected, by means of a pivot pin 31, to the upper end of a slotted segment lever 32, the lower end of which is pivoted to the upright portion of the arm by means of a pivot pin 33. A segmental slot 34 in the lever 32 is arranged to adjustably engage one end of a link 35 by means of a pivot bolt 36, the other end of the link being pivotally connected by means of a pivot pin 37 to one end of a short crank arm 38, the lower end of which is rigidly connected to one end of a shaft 39 rotatably mounted in the upright portion of the arm, the backwardly extending portion of which is suitably recessed together with the bed plate to permit of free movement of a crank arm 40 the upper end of which is rigidly secured to the shaft 39 adjacent its rear end. The lower end of the crank arm 40 is provided with a

roller 41 arranged to engage a cam groove 42 in a circular cam 43 secured to an auxiliary shaft 44 mounted in the bearing blocks 13 and 14. Mounted on the auxiliary shaft 44 is a gear 45 which is arranged to be engaged by a pinion 46 mounted on the main driving shaft 12.

The rotation of the main driving shaft 12 acts through the pinion 46, gear 45, cam 43 and connecting parts to oscillate the needle oscillating lever 25 whose oscillations act to oscillate the needle actuating lever 19 and thereby the needle 21 as the needle bar is reciprocated.

15 The oscillations of the needle can be regulated by setting the pivot bolt 36 at different positions in the segmental slot 34, any ordinary throw of the needle can be obtained in this manner, further regulations of the 20 throw of the needle can of course be obtained by varying the cam groove in the cam 43.

In the present instance the looping mechanism comprises a rotary hook or loop taker 25 having a vertical shaft 48 rotatably mounted in a bearing block 49. The shaft 48 is provided intermediate of its length with a bevel pinion 50 which meshes with a bevel gear 51 mounted on the main driving shaft 12 adjacent the end thereof. The relative sizes of the bevel pinion 50 and the bevel gear 51 to form a hemstitch being such as to impart two rotations to the loop taker 47 to each complete stroke of the needle bar.

35 In accordance with the present invention the cam groove 42 in the cam 43 is cut to oscillate the needle 21 at proper intervals to form a hemstitch. In the present instance the cam groove 42 is cut to give a substantially straight up and down movement to the needle when a stitch is made on the hem fold of the material, and to oscillate the needle when stitches are made off the hem fold, the cam groove being suitably cut 40 to oscillate the needle to place two stitches off the hem fold to one on.

In that the needle 21 is moved substantially straight up and down when placing a 50 stitch on the hem fold the needle thread does not bind and break during this portion of the stitch even at very high speeds, it being customary to provide a small longitudinal recess on each side of the needle, into which the needle thread fits, to obviate the 55 binding of the needle thread between the needle and the material.

After the needle 21 has been actuated by the cam groove 42 on the cam 43 to place a 60 stitch on the hem fold, the cam groove 42 on the next downward movement of the needle acts to oscillate the needle to place a stitch off the hem fold. After the needle has passed through the material to place the 65 stitch off the hem fold the cam groove 42, on the further downward movement of the

needle acts to oscillate the needle toward the rotary hook or loop taker 47 to permit the needle thread to be engaged thereby, in which position the needle is moved by the action of the cam groove 42 substantially straight up and down at the end of its downward movement and at the beginning of its upward movement. On the further upward movement of the needle the cam groove 70 75 acts to again oscillate the needle away from the loop taker to permit the needle to come out of the material at substantially the same point where the needle entered the material off the hem fold, so as to obviate any tendency to bind the needle 80 thread between the needle and the material to cause the thread to break.

After the needle 21 has been oscillated by the action of the cam groove 42 to place one stitch off the hem fold the cam groove 85 90 95 42 again acts in exactly the same manner to place another stitch off the hem fold, which operation is followed by another series of operations to place another stitch on the hem fold and two off, as before described.

The oscillations of the needle back and forth by the action of the cam groove 42 every time a stitch is placed off the hem fold so that the needle enters and leaves the material at substantially the same point obviates any tendency to bind the needle 95 100 thread between the needle and the material to cause the thread to break even at the highest speeds.

When the machine is run at very high speeds it is extremely important that there be no binding of the needle thread as it passes through the material, as the slightest binding of any kind will cause it to break while it is true that the needle is ordinarily provided with a longitudinal recess on both sides, these recesses act to prevent binding only when the needle is reciprocated straight up and down in the material; when however the needle is oscillated to place a stitch off the hem fold the movement of the needle inward to draw the needle thread into engagement with the hook or loop taker, crowds the material up against the needle in such a manner as to bind the needle thread when the needle is withdrawn from the material if this crowding of the material is not relieved.

In accordance with the present invention the crowding of the material against the needle as the needle is withdrawn after placing a stitch off the hem fold is accomplished, as above described, by cutting the cam groove 42 in the cam 43 so that the needle leaves the material at substantially the same point as the needle entered the material, or at such a point as near where the needle originally entered as to be beyond where the material will bind or break the needle thread. The crowding of the material 110 115 120 125 130

against the needle is not a serious matter when the machine is run at comparatively low speeds but when the machine is run at very high speeds it is absolutely essential that this crowding of the material which acts to bind the needle thread be obviated.

In the present instance the feeding mechanism comprises a feed bar 52 having suitable feed points 53 situated on the top surface of a recessed feed dog 54 secured to said feed bar. One end of said feed bar is pivoted, by means of a bearing pin 55, to the upper ends of two short arms 56, the other ends of which are secured to a rock shaft 57 rotatably mounted on bearing pins 58 secured to bearing blocks 59 and 60 secured to the bottom of the bed plate. The rock shaft 57 has adjustably secured thereto a slotted arm 61 in which is adjustably secured one end of a link 62 by means of a pivot bolt 63 the other end of the link 62 being pivoted to one arm of an L shaped lever 64 the center of which is secured to one end of a sleeve 65 rotatably mounted on a shaft 66 secured to the bearing blocks 13 and 14. The other arm of the L shaped lever 64 is provided with a roller 67 which engages a cam groove 68 situated on the side of the gear 45 mounted on the auxiliary shaft 44.

The rotation of the main driving shaft 12 acts through the pinion 46, gear 45, cam groove 68, roller 67 and connecting parts to move the feed bar 52 and with it the feed dog 54 back and forth at stated intervals to feed the material backward or forward as may be required. In the present instance the cam groove 68 is arranged to move the feed dog 54 back and forth for every complete stroke of the needle bar. The back and forth movement of the feed dog is regulated by adjusting the pivot bolt 63 in the slotted arm 61 to give any desired feed movement to the feed dog.

The other end of the feed bar 52 is slotted to receive a cross head 69 which is pivotally secured to one end of a short arm 70 the other end of which is secured to a rock shaft 71 rotatably mounted on bearing pins 72 secured to bearing blocks 73 and 13 secured to the bottom of the bed plate. The rock shaft 71 has secured thereto one end of a short arm 74 the other end of which is provided with a roller 75 which engages a cam groove 76 in a segmental cam 77 secured to a rock shaft 78 rotatably mounted on bearing pins 79 secured to bearing blocks 73 and 13. The segmental cam 77 is provided with a slot 80 which engages a cross head 81 pivoted on a disk 82 secured to the end of the auxiliary shaft 44.

The rotation of the main driving shaft 12 acts to rotate the auxiliary shaft 44 and it acts through the cross head 81, segmental cam 77 and connecting parts to depress the feed bar 52 and with it the feed dog 54 at

stated intervals to feed the material backward or forward as may be required. In the present instance the cam groove 76 is arranged to depress the feed dog 54 to feed the material forward two steps to one step 70 rearwardly.

In accordance with the present invention the upward and downward movement of the feed dog 54 into and out of engagement with the material is regulated to give a relatively slow upward movement of the feed dog, as it engages the material, with a corresponding rapid downward movement of the feed dog as it disengages the material.

The relatively slow upward movement of the feed dog acts to force the material against the bottom of a suitable double presser foot 83 with little or no jar and accordingly without injury to the material, it being important at high speeds to avoid the jar incident to a too rapid engagement of the feed dog with the material which would act to force the material against the bottom of the presser foot in many instances with sufficient force to cut the same.

The corresponding rapid downward movement of the feed dog acts to disengage the material instantly without jar or shock allowing the time thus saved to be used on the relatively slow upward movement of the feed bar.

By referring to the drawings it will be seen that when the cam groove 76 acts to depress the feed dog 54 the cross head 81 on the disk 82 is moving in that portion of the slot 80 of the segmental cam 77 which is adjacent the rock shaft 78, which acts to give a rapid downward movement to the feed dog; when however the cam groove 76 acts to raise the feed dog, the cross head 81 on the disk 82 is moving in that portion of the slot 80 of the segmental cam 77 which is away from the rock shaft 78 which acts to give a relatively slow upward movement to the feed dog.

In the present instance the double presser foot 83 comprises two presser shoes 84 each of which is suitably pivoted midway of their length to the lower curved ends of shoe arms 85 the upper ends of which are secured to the lower ends of independent presser foot bars 86 each of which is slidably mounted in the end of the overhanging arm 2. The upper end of each of the presser foot bars are preferably made hollow and arranged to enclose coiled springs 87 arranged to be engaged by pins 88 pressed downward by means of suitable caps 89 which screw into the arm 2 to force the shoes 84 into engagement with the material on the feed dog. When in the operation of the machine the feed dog is lowered the overhanging sides of the presser shoes rest upon the feed plate 90.

The presser shoes 84 are arranged to act on the material entirely independent of each

other but the same are arranged to be lifted when not in use by means of a latch 91 pivoted to the arm 2 which engages a projection 92 secured to a double collar 93 mounted on both presser foot bars and arranged to be secured to one and slidably mounted on the other. A similar double collar 94 is also provided which is mounted on both presser bars and spaced away from the double collar 93 the same being secured to the opposite presser foot bar and slidably mounted on the other so that the latch 91 will operate both presser shoes at the same time leaving the presser shoes when in operative position to act independently, the double collars 93 and 94 acting to brace the presser foot bars one against the other.

It is to be noted that the presser foot bars 86 are slidably mounted in the end of the arm as nearly adjacent the needle bar 8 as possible, in order to give as nearly as possible a direct upward thrust to the presser bars when the presser shoes are engaged on the upward movement of the feed dog. The mounting of the presser foot bars so nearly adjacent the needle bar is made possible by the fact that the needle bar is reciprocated by the rocking of the actuating shaft 3, less space being required for a reciprocating connection than otherwise would be the case if the actuating shaft 3 was rotated. This arrangement of the presser bars prevents excessive vibration of the presser foot and enables the machine to be run at very high speeds with a uniform feeding of the material.

The take up mechanism comprises a take up arm 95 arranged to extend upward through a slot 96 in the bed plate, the lower end of said take up arm is integrally secured to a short shaft 97 rotatably mounted in the bearing block 14. The shaft 97 has secured thereto one end of a short arm 98, the other end of which is pivoted by means of a ball joint 99 to one end of a link 100 the other end of which is pivoted by means of a ball joint 101 to the end of an adjustable arm 102 secured to a short shaft 103, rotatably mounted in the bearing block 14. The end 50 of the shaft 103 which projects beyond the end of the bearing block 14 is secured to one end of a guide rod 104 upon which is slidably mounted a slide sleeve 105 having an extended portion 106 which is pivoted by means of a pivot pin 107 to an extended portion 108 on the lower end of the connecting rod 10.

The rotation of the main driving shaft 12 in a clockwise direction acts through the medium of the slide sleeve 105 to oscillate the guide rod 104 which acts through connecting parts to oscillate the take up arm 95. The position of the slide sleeve 105 on the end of the connecting rod 10 adjacent the crank 11 with the corresponding position of

the connecting parts acts to give a rapid movement to the take up arm when the same is moving from left to right to take up additional thread and a relatively slow movement when the take up arm is moving from right to left to let out the thread, together with a gradual acceleration of the take up arm near both ends of its movements.

In other words, the motion of the take up arm is slow while the hook or loop taker 47 is taking the loop of the needle thread which takes place when the take up arm is moving from right to left, while for drawing the stitch tight, which takes place when the take up arm is moving from left to right, the movement of the take up arm is extremely rapid. It will be observed that the slide sleeve 105 is at the lower portion of the guide rod 104 adjacent the shaft 103 when the take up arm is moving from left to right and also near both ends of its movements, permitting relatively fast movement of the take up arm during this time, when however the slide sleeve 105 is at the upper portion of the guide rod 104 the take up arm is moving from right to left, permitting relatively slow movement of the take up arm during this time.

The machine above described is capable of running at the rate of forty-five hundred revolutions a minute upward to five thousand revolutions a minute with practically no vibration.

While the invention has been described with particular reference to the details of construction, the same is not to be considered as limited thereto, as many changes can be made and still fall within the scope of the invention set forth in the following claims.

What I claim is:

1. A hem stitching machine including in combination, a reciprocating needle bar, means for holding the needle connected thereto, a rotary hook located to one side of the line of feed of the material and adapted to engage the thread carried by the needle, and means for oscillating said needle to make lateral stitches in the material, said oscillating means being arranged to move the needle when in the material toward and away from said hook, said last named means serving to position the needle thread in uncrowded relation to the side of the material upon the withdrawal of the needle from the material, whereby the needle thread will have a free action at relatively high speeds of the machine.

2. A hem stitching machine including in combination, a reciprocating needle bar, means for holding a needle connected thereto, means arranged to engage the thread carried by the needle, said means being adapted to engage the needle thread to one side of a plane passing through the center of the line of

- feed of the material, and means for oscillating said needle to make lateral stitches in the material, said oscillating means being adapted to move the needle when in said material and off the hem fold toward and away from said second named means, said last named means serving to return the needle to a position for permitting its withdrawal from the material at substantially its point of entry with the needle thread uncrowded against the sides of the material for permitting free action thereof at relatively high speeds of the machine.
3. A hem stitching machine including in combination a reciprocating needle bar, means for holding a needle connected thereto, means arranged to engage the thread carried by the needle, said means being adapted to engage the needle thread upon one side of the line of feed of the material, and means for oscillating the needle to make lateral stitches in the material, said oscillating means being arranged to move the needle when in the material toward and away from said needle thread engaging means, said oscillating means acting to cause the withdrawal of the needle from the material with the needle thread uncrowded from against the side of the material to permit free action of said thread at high speeds, and means for adjusting the relative lateral movements of the needle in the material.
4. A hem stitching machine including in combination a needle bar, a needle actuating means connected to the needle bar, means arranged at one side of the line of feed for operative engagement with the thread carried by the needle, a lever pivotally connected to the needle bar and operated to oscillate the needle laterally, and means including an adjustable lever for oscillating the first named lever whereby the needle is moved when in the material toward and away from said needle thread engaging means and caused to enter and leave the material with the needle thread uncrowded from against the sides of the material to permit free action of the needle thread at relatively high speeds of the machine.
5. A hem stitching machine including in combination a needle bar, an actuating means connected to the needle bar, a rotary hook arranged to engage the thread carried by the needle, a lever pivotally connected to the needle bar, and means including a lever and link connection for the first mentioned lever, said means being adapted to oscillate the needle when in the material toward and away from said rotary hook to cause the needle to enter and leave the material at substantially the same point thereby permitting the needle thread to be positioned in uncrowded relation to the sides of the material during the withdrawal of the needle.
6. A sewing machine including in combination a needle bar, a needle actuating means connected to the needle bar, an L-shaped lever having its upper end pivotally connected to the machine, a needle actuating lever pivoted to the needle bar and having its upper end slidably connected to said L-shaped lever, a link pivotally connected to the L-shaped lever, a crank operating said lever, and means including a cam for operating the crank whereby the needle actuating lever is vibrated and the needle caused to move laterally to and fro while in the material so as to position the needle thread in uncrowded relation to the side of the material upon the withdrawal of the needle.
7. A hem stitching machine including in combination, a needle bar, an actuating shaft connected to said needle bar, means for oscillating said needle shaft to reciprocate said needle bar, a movable hook for engaging the thread carried by the needle, means for vibrating the needle when in the material toward and away from said hook said vibrating means acting to position the needle thread in uncrowded relation to the side of the material when the needle is withdrawn for preventing breakage of said needle thread at relatively high speeds of the machine, a feed dog, means for oscillating said dog to feed the material through the machine, a presser foot, and means for mounting said presser foot immediately adjacent said needle bar and directly above said feed dog.
8. A hem stitching machine including in combination a needle bar, a needle actuating lever pivotally connected to said needle bar, an oscillating lever movably connected to said needle actuating lever, a rotary hook adapted to engage the thread carried by the needle, and means for operating said oscillating lever to move said actuating lever when the needle is in the material, said means being adjustable and serving to move the needle while in the material a predetermined distance toward and away from the said rotary hook, the movement of the needle away from said hook acting to position the needle thread in uncrowded relation from against the sides of the material to permit free action of the needle thread and prevent breakage thereof at relatively high speeds of the machine.
9. A hem stitching machine including in combination a reciprocating needle bar, means for holding a needle connected thereto, means arranged to engage the thread carried by the needle, said means being adapted to engage the thread upon one side of the line of feed of the material, and means for oscillating the needle to make lateral stitches in the material, said means including a cam adapted to move the needle when in the material toward and away from said needle thread engaging means, said cam being dependent upon the withdrawal of the needle.

signed to position the needle thread in uncrowded relation with respect to the sides of the material upon the withdrawal of the needle for permitting free action of said needle thread at high speeds without breakage.

In testimony whereof I have signed this

specification in the presence of two subscribing witnesses.

JAMES LEATHEM.
